BOOKSTACK

John Howard Ford, Washington, D. C.

Application August 25, 1932, Serial No. 630,470

17 Claims. (Cl. 211—136)

The invention to which the following description relates deals with improvements in adjustable shelving and particularly in bookstacks. The design and arrangement of satisfactory shelving for the storage of books in large quantities is a problem which has up to the present, been considered as demanding particular forms of building construction. It has been considered necessary to especially design buildings where library shelving is to be installed. This impairs the usefulness of the building for other purposes and necessitates special forms of construction. In like manner too frequently the book shelving is considered a part of the building. In this way it is not readily adaptable for installation in ordinary structures.

It is an object of my invention to provide a bookstack which may be readily assembled and installed in the usual forms of building construction and without special modification of the latter. It is also an object of my invention to provide a bookstack which may be varied in its size, proportions and arrangement so that it may be fitted to the area it is to occupy or subsequently installed with equal efficiency in a different location.

A further object of my invention is the design of a bookstack which may be wholly or to a great extent supported from above such as the ceiling, girders or the like of a building so that no permanent modification of or attachment to either the floor or columns is required. In this way the floor and columns are kept clear and easily cleaned.

In this way a bookstack is provided which may be wholly removed from any bay at any time, leaving the cleared space entirely free from bookstack parts and ready for other occupancy, and the said bookstacks may be readily reerected in the same or other space with ordinary tools.

Among the further objects of my invention is a bookstack assembled from ordinary shapes of sheet metal and angle forms without special fabricating equipment.

The bookstack so designed is economical of manufacture and meets the demand that it shall be dust free and shall have no concealed crevices or openings which might harbor insects.

As illustrating the preferred form of my invention I have shown various details thereof in the following drawings in which

Fig. 1 is a side elevation of the assembled bookstack;

Fig. 2 is a horizontal section taken on the line 55 2—2 of Fig. 1;

Fig. 3 is a vertical section taken on the line 3—3 of Fig. 2;

Fig. 4 is an end elevation of the shelf;

Fig. 5 is a front elevation of the shelf and its mounting;

Fig. 6 is a detailed vertical section of the rear shelf support;

Fig. 7 is a diagrammatic front elevation of a modified form of the bookstack supported from a flat ceiling;

Fig. 8 is a similar end view of the same;

Fig. 9 is a vertical end view of the modified form of the bookstack partly in cross-section;

Fig. 10 is a plan view of the same along the line 10—10 of Fig. 9;

Fig. 11 is a detailed front elevation of the shelf mounting, and

Fig. 12 is an inferior perspective view of the modified form of shelf.

Referring to the form shown in Fig. 1 it will be seen that the bookstack is mounted in the space between the upper floor 13 and the lower floor 14. Vertical columns extend between the ceiling or the girder 15 and the floor at desired intervals and are in the form of girders 14 or the like. The ceiling of the upper floor 13 has a depending girder 15 in the form of an I-beam. This girder has a lower flange 16 which is used in the mounting of the bookstack.

The bookstack is assembled either single or double ended and consists of a top cross bar 17 generally in the form of a downwardly open channel which is shaped or bowed in the case of its being used with the girder 15. Where the bookstack is supported directly from a flat ceiling the channel bar 17 is of course correspondingly straight. In the case of a double ended bookstack, the mid-portion of the top bar 17 carries a U-bolt 18 which extends upwardly and passes through the flanges 16 of the girder 15. The two ends 13, 13 of the U-bolt carry nuts 19, 19 by which the top bar 17 is firmly clamped to the bottom of the flanges 16. In this way the entire end section 20 of which the bar 17 forms a part is supported from and attached to the girder 15.

A bar 21 forms the bottom member of the end section 20. The bar 21 is likewise preferably of channel shape opening upwardly. Extending vertically between the top bar 17 and the bottom bar 21 are end bars 22 and 23. These latter bars have a series of pins or lugs 24, 24 extending at regular spaced distances horizontally outwardly from the bars 22, 23. Face panels 25, 26 are fastened by riveting, welding or the like upon the opposite sides of the bars 17, 21, 22, and 23. In

9445 9450 9455 9460

this way the end sections 20 are formed as hollow dust-proof sections with smooth outer surfaces.

For greater strength intermediate reinforcing channels 27 are attached between the inner sides of the panels 25, 26.

The panels 25, 26 also carry parallel metal strips 28, 28 which extend for the full height of the panels. Each strip 28 carries a series of outwardly extending steps and lugs 29. As illustrated in greater detail in Fig. 6 the strip 28 is punched outwardly to form the step 29. This step has a front slope 30 and a top seat 31. The latter forms the support for the rear of the shelf. The strips 28 are applied to the face panels by welding, riveting or the like with the steps 29 properly positioned with respect to the ends 23 which form the support for the shelves at the front. The end sections 20 are held in spaced position one from the other by means of top spacer bars 32 which are bolted or otherwise fastened to the ends of the upper bar 17. In like manner spacer bars 33 connect the ends of the bottom bars 21.

The bookstack is braced against swinging movement by a strut 34 extending downwardly from the end sections 20 in the vertical plane of the girder 14' as shown in Fig. 7. The struts 34 have foot extensions connected to the girder 14' by means of the bolts 36.

In many instances it is desirable to separate the opposite sides of the double bookstack. This is provided for by the use of a sheet metal vertical partition 37, the type shown being a known form. The upper end of the partition 37 is wrapped around a horizontal bar 38 the ends of which rest in stirrups or saddles 39 in the upper sides of the face panels. The lower ends of the partitions 37 have lugs 40 by means of which the partition is bolted to the side panel at the lower end.

While the fabrication of an end section 22 in the manner above described is entirely satisfactory, yet there are some instances where such forms are not necessary but may be replaced by end sections formed of a single piece of sheet metal of appropriate gauge. In Figs. 7 to 11 inclusive I have shown such an arrangement. As illustrated in Figs. 7 and 8 this modified form is shaped at the top to conform to a flat ceiling against which it is to be applied. For this reason the end section 41 has a top that is straight rather than bowed as is the case in Fig. 1. The top bar 42 is a flat strip applied to the top edge of the section 41 by welding or other suitable means. Intermediate the length of the bar 42, the latter is punched to provide countersunk or other shaped openings 43 in which the heads of the bolts 44 are seated. As these bolts 44 are applied to the bar 42 before the latter is attached to the section 41, it follows that bolts 42 are rigidly held in parallel vertical positions against the possibility of turning.

The mode of suspending the bookstack is the same as in the form first described. The end section is raised against either the flange 16 or the ceiling 45 and the bolts 44 pass through appropriately formed holes in the girder or ceiling and the sections 20 and 21 can then be drawn up tightly by appropriate nuts.

In Fig. 8 I have shown diagrammatically two successive floors 13 and 45 in the lower instance illustrating the mode of suspending a bowed bookstack section while in the upper instance the section 41 is of the flat topped type.

The spacer bars 32 are applied to the down-

wardly extending ends 46 of the top bars 42. Angle iron ties 47 serve to anchor the bar ends 46 and the spacer bars 32 against the ceiling.

The bottom of the section 41 has a bottom bar 21 and spacing bars 33 serve to brace the end bars 21. The bookstack is braced against swinging movement as shown in Figs. 7 and 8 by the brackets or struts 34 attached with bolts 36 to the bottoms of the terminal end sections which have been marked 41' and to the adjacent building element such as a wall, column or girder 14'. It is further braced against twisting by similar brackets or angle-iron ties 47 attached at the top of the terminal end sections 41' and to the ceiling member 45. The spacer bars 32 and 33 connect the terminal end sections 41' and the intermediate end sections 41 in each bay, and are of suitable shape and rigidity for the length of the bays, thus serving to maintain the intermediate end sections 41 in alignment with the terminal end sections 41'. By this arrangement no part of the bookstack rests on the floor but the latter is maintained free from obstruction and readily accessible for cleaning and the like.

As illustrated in Figs. 9 and 10 the side edges of the section 41 have integral horizontally extending lugs 48 which serve as seats for the shelves. Inwardly of the side edges of the section 41 and suitably spaced from each row of lugs 48 is a corresponding series of brackets. These brackets are made by slotting the sheet metal to form pairs of adjusting tongues 49 and 50. Of each pair of tongues the lowermost 49 is bent in one direction while the uppermost 50 is bent in the opposite direction. Both tongues 49 and 50 have extensions or ends 51 which are again bent into planes parallel to that of the section 41 as shown in dotted lines in Fig. 10. The extension ends 51 are spaced from the adjacent sides of the surfaces of the sections 41 by a distance proportioned to the gauge of the metal of which shelves are formed so that flanges on the shelves may interlock between the sections 41 and the extensions 51 and the several sections 41 will thus be held in definite spaced relation governed by the dimensions of the intervening shelf. In this way the sections 41 are reinforced and prevented from any tendency to buckle or warp either by reason of peculiarity in manufacture or the stresses imposed by the shelf loads.

Referring to Figs. 1 to 5 inclusive I have illustrated metal shelves which are adapted for assembly with the end sections 20 to form the complete bookstack. The shelf denoted generally by the numeral 52 is made of stamped sheet metal of appropriate gauge. The metal is slotted as indicated at 53 and formed to provide a series of ribs 54 parallel with the front edge 55. The material between the adjacent ribs 54 is bent downwardly into a concave channel 56 the bottom of which is formed by the slot 53. This insures proper support for the books on the shelf, prevents accumulation of dust and insures the bottom of the shelf of freedom from rough edges which might damage the books or injure the one using the shelf. A bar 57 is fitted beneath the front edge 55 of the shelf. The bar extends beyond the length of the shelf having two ends 58 and 59. As shown in Fig. 2 the right end 58 extends coincidental with the main portion of the bar 57. The left end 59, however, is offset a distance equal to the gauge of the metal of the bar 57. This allows the overlapping of the bars of successive shelves as shown in Fig. 2. In order to properly seat upon the round lugs 24, the ends 75

57 and 58 are concaved as shown at 60. It will be readily apparent that by such an arrangement the shelves are centered with respect to the lugs 24 and that any increase in shelf load will tend to correspondingly increase the accuracy with which the bar 57 is supported on the lugs 24.

The front edge 55 of the shelf has a flange folded down over the bar 57 and up in the rear of the latter as shown in Fig. 3.

10 The rear edge 62 of the shelf has a corresponding flange 63 folded downwardly and up around a rear bar 64. This bar 64, however, does not extend the full length of the shelf but terminates short of the corners thereof in order to allow relative movement between the depending flanges on the rear ends of the shelf.

20 The shelf has opposite ends 65 and 66 which are also formed by bending down flanges from the sheet metal. The front ends of the flanges 65 and 66 may if desired be welded or otherwise attached to the bar 57 or the flange 61. As shown in Fig. 2 the flange 66 is spaced from the flange 61 and the top of the shelf cut away to accommodate the offset end 59 of the bar 57. In 25 the rear, however, the flanges 65 and 66 terminate short of the rear flange 65 in a spaced depending tongue or detent 67. The flange is cut away in front of the tongue 67 to provide a slope 68 and a recessed seat 69 which latter conform 30 respectively to the incline 30 and seat 31 on the brackets 29.

35 It is possible to slide this shelf in place from the front of the bookstack between the end sections 20. The depth of the rear flange 63 permits the latter to pass between adjacent brackets 29 and to drop behind them with the flanges 65 and 66 resting on the brackets by means of the seats 69. In this position the tongue 67 prevents sliding movement of the shelf in a forward direction 40 or in other words locks the shelf into place.

45 During this operation the ends 58 and 59 of the front bar 57 fit over the lugs 24 with the end 58 in place in front of the offset end 59 of the adjacent shelf section as shown in Fig. 2.

50 Any slight inequality in manufacture or assembly will be corrected and the four points of support all brought into normal operation by the slight distortion in the shelf made possible through the open corners.

55 These shelves may be installed in any desired spacing arrangement and where a double section is used such as illustrated in Fig. 1, by omitting partition 37, shelves on both sections may be on the same level to provide in effect a single shelf of double depth.

60 In the modification shown in Figs. 7 to 12 inclusive the same general design of shelf is possible. The shelf 70 is made of sheet metal having a series of parallel ribs 71 produced by slotting the metal and forming the depending grooves 72 having inwardly turned ends 73 thus forming a slot 74. The front flange 75 of the shelf is attached to and folded down over the front bar 57. This bar also has one end 58 and the opposite end 59 offset as above described. The rear flange 76 is cut away at each corner to provide necessary clearance over the tongues 49 and 50. As these tongues are of different elevations it follows that the cut-away portion in one instance is shallow 70 and in the other instance deep.

75 One side flange 76' is bent down and provides the cut-away edge 77 and a seat 78 which is adapted to fit over the lower tongue 49.

The opposite end of the shelf is bent down to form the flange 79. This flange is also cut

away at the rear to form the elevated edge or 50 detent 80 and a recessed seat 81. The seat 81 is proportioned to fit over the upper tongue 50. When the flanges are seated upon the tongues 49 and 50 the flanges are behind the extensions 51 so that the latter serve to hold the end section 41 into a vertical position close to the shelf ends and 55 free from buckling or warping.

As the ends of the shelves are fitted over the 10 tongues 49 and 50, the front bar 57 fits in between the lugs 48 upon which latter the ends 58 and 59 rest. In Fig. 11, I have shown the ends 58 and 59 to have tapering bottom edges ending in a substantially horizontal seat 82. In this way the weight of the shelf tends to accurately 15 center the shelf with respect to the end sections 41 and maintain the end sections 41 accurately at their predetermined spacing.

20 By building up a bookstack in a manner apparent from the above description it is found that 25 material advantage is obtained due to the substantial reduction in the material used and the labor of installation. When considerable shelf space is to be provided the weight of the material is a consequential item both for the cost of the 25 bookstack and on account of the load to be imposed on the floor. With the use of fabricated sheet metal as shown in Fig. 1 or the single stamped metal ends 41, it is possible to materially 30 reduce the weight of the bookstack without sacrificing strength or rigidity.

35 This bookstack is assembled from stock material which is readily available. The fabrication of the several parts is adapted for machine operation at low cost and permits working to close 35 dimensions and accurate proportions.

40 The bookstack is exceedingly flexible in its arrangement as shown in Figs. 7 and 8. The stack may be installed or removed without material change in the usual building construction.

45 As assembled the form of shelves and their mounting upon the end sections is such as to increase the stability of the stack with increase of the shelf load. At the same time the stack is maintained free from dust and accessible for 50 ready use or cleaning.

55 The essential ideas of this invention while 50 illustrated by way of example only are capable of great variation in size, proportion and minor details without departing from the scope of the 55 invention as defined in the following claims.

What I claim is:—

1. A bookstack comprising two or more end sections, each formed with upper and lower end bars, means extending upwardly from the upper end bar for suspending the section, spacing bars connecting adjacent end sections, a face panel on each of the sections, a partition removably held by said end sections, shelf-supporting means on the face panels, other shelf-supporting means on the side edges of the sections, shelves carried by said shelf-supporting means and means on said shelves to prevent the end sections from moving away from their normal positions.

2. An end section for a bookstack comprising upper and lower end bars, means extending upwardly from the upper end bar for suspending the section, a panel connecting the said end bars, shelf-supporting means extending laterally from the surface of said panel, and other shelf-supporting means extending from one of the side edges of said panel.

3. An end section for a bookstack comprising upper and lower end bars, means extending upwardly from the upper end bar for suspending

- the section, partitioning means connecting the said end bars, shelf supporting means extending laterally in opposite directions from said partitioning means and other shelf-supporting means 5 extending outwardly from the side edges of the section.
4. An end section for a bookstack comprising upper and lower end bars, means on the upper end bar for suspending the section, spaced parallel side bars extending from the upper to the lower end bars, face panels attached to opposite sides of the said side and end bars, and shelf-supporting means on one of said panels. 10
5. An end section for a bookstack comprising upper and lower end bars, means on the upper end bar for suspending the section, spaced parallel side bars extending from the upper to the lower end bars, face panels attached to opposite sides of the said side and end bars, shelf-supporting means on one of the said panels and shelf-supporting means on one of the said bars. 15
6. An end section for a bookstack comprising upper and lower end bars, means extending upwardly from the upper end bar for suspending the section, a panel connecting the said end bars, adjacent tongues extending laterally in opposite directions from the panel and shelf-supporting means extending outwardly from the side edges of the panel. 20
7. An end section for a bookstack comprising upper and lower end bars, means extending upwardly from the upper end bar for suspending the section, a panel connecting the said end bars, adjacent tongues extending laterally in opposite directions from the panel, offset ends on the tongues spaced parallel to the panel, and shelf-supporting means extending outwardly from the side edges of the panel. 25
8. An end section for a bookstack comprising upper and lower end bars, a U-bolt extending upwardly from the upper end bar for suspending the section, side bars connecting the end bars, face panels attached to opposite sides of the bars, a member vertically disposed on one of said panels, shelf-supporting means on said member, and shelf-supporting means on one of said side bars. 30
9. An end section for a bookstack comprising upper and lower end bars, a U-bolt extending upwardly from the upper end bar for suspending the section, side bars connecting the end bars, face panels attached to opposite sides of the bars, a reinforcement between said panels, a member vertically disposed on one of said panels, shelf-supporting means on said member, and shelf-supporting means on one of said side bars. 35
10. In combination, end sections for a bookstack, each comprising supporting means, a panel and shelf-supporting means on the panel; a shelf formed of sheet metal having down-turned flanges, recessed seats in said flanges for resting on said shelf-supporting means, means on said flanges for locking with said shelf-supporting means to prevent disengagement of the shelf from the panel and spacer bars attached to and extending between said end sections. 40
11. In combination, end sections for a bookstack, each section comprising a panel and shelf- 45
- supporting means on the panel, a shelf, seating means on the shelf for engaging said shelf-supporting means, said seating means having downwardly concave or inclined faces such that the weight of the load on the shelf serves to insure the accurate centering of the seating means on the shelf-supporting means. 5
12. In combination, end sections for a bookstack, each section comprising a panel and shelf-supporting means on the panel, spacer bars connecting adjacent end sections to maintain the desired distance between the shelf-supporting means on adjacent sections, a shelf, seating means on the shelf for engaging said shelf-supporting means, said seating means having downwardly concave or inclined faces such that the weight of the load on the shelf serves to insure the accurate centering of the seating means on the thus spaced shelf-supporting means. 10
13. A bookstack adapted for use in a room having vertical members and a ceiling member, said bookstack comprising a plurality of terminal and intermediate end sections, means at the top of each end section for suspending the section, means attached to one terminal end section for holding it spaced from the vertical member of the room and against horizontal displacement, means on an end section to space it from the ceiling member and against torsional displacement, spacer bars connecting adjacent end sections, shelf-supporting means on the end sections, and shelves carried by said shelf-supporting means. 15
14. An end section for a bookstack comprising upper and lower end bars, a panel connecting the end bars, means on the upper end bar for suspending the section and shelf supporting means on the panel, said end bars extending outwardly beyond the side edges of the panel for attachment purposes. 20
15. An end section for a bookstack comprising upper and lower end bars, means on the upper end bar for suspending the section, side bars connecting the end bars, face panels attached to opposite sides of the bars, shelf-supporting means on one of said face panels and cooperating shelf-supporting means on one of the said side bars. 25
16. A bookstack having end sections comprising thin vertical metal panels capable of sustaining the tension caused by the hanging weight of the shelf-load, means on the upper end of each panel for attachment to a support, shelves, means on the panels for supporting the shelves and spacer bars attached to and extending between adjacent end sections. 30
17. An end section for a bookstack comprising a thin vertical metal panel capable of sustaining the tension caused by the hanging weight of the shelf-load but free to flex laterally, a reinforcement across the upper end of the panel 35 sustaining the bending stresses from the tension in the panel, said reinforcement extending outwardly beyond the side edges of the panel for attachment purposes, suspending means on the upper end of the panel and means on the panel for supporting a shelf. 40

JOHN HOWARD FORD.
